VARIABLE SPEED GOVERNOR

Filed Oct. 21, 1929

UNITED STATES PATENT OFFICE

WALTER SCHMID, OF PHILADELPHIA, PENNSYLVANIA, ASSIGNOR TO WESTINGHOUSE ELECTRIC & MANUFACTURING COMPANY, A CORPORATION OF PENNSYLVANIA

VARIABLE SPEED GOVERNOR

Application filed October 21, 1939. Serial No. 401,219.

My invention relates to a regulating mechanism, more particularly to a speed-responsive governor for a prime mover and it has for its object to provide apparatus of the character set forth capable of wide variation in the setting thereof.

A more specific object of my invention is to provide a speed governor which will govern within the same percentage of regulation 10 at any one of a number of widely varied speed settings.

Satisfactory governing devices have been developed for governing prime movers at a given speed. Considerable difficulty has been 15 experienced, however, in designing governors for widely varying speeds. This difficulty is due to the fact that the variations in governing force are much greater at higher speeds than at lower speeds, whereas the 20 spring which opposes the governing force is capable of providing but one scale, which may be suitable for one speed but unsuitable for other speeds.

In accordance with my invention, I provide 25 a regulating mechanism including pressure-responsive elements subjected to the variable fluid pressure in accordance with the speed the mechanism is to regulate, which, in the case of a speed governor, varies as a function of the speed, usually as the square of the speed. I also provide means for varying the area of surface of the pressure-responsive element on which the variable fluid pressure is effective to bias said element. In this way, 30 the same total governing force may be obtained for various fluid pressures corresponding to various speeds, and the same governing action may therefore be obtained at widely varying speeds.

40 The above and other objects are effected by my invention, as will be apparent from the following description and claims, taken in connection with the accompanying drawings and forming a part of this application, in which:

Fig. 1 is a side elevation of a prime mover having a speed governor in accordance with my invention; and,

Fig. 2 is a sectional view of the speed gov- 50 ernor.

Referring now to the drawing, more in detail, I show a steam turbine 10 having a steam supply conduit 11 and a discharge conduit 12. An admission valve 13 is interposed in the conduit 11 to regulate the admission of motive fluid to the turbine. The admission valve 13 is controlled and operated by a 55 governor 14. The governor 14, in turn, is controlled by fluid pressure developed by a pump 15 driven directly by the rotor shaft 16 of the turbine. The fluid pressure is conveyed to the governor through a conduit 17.

Referring now to Fig. 2, the governor 14 includes a cylinder structure 18, which is bored on the interior thereof to form cylinder walls 19, 20, 21 and 22, of progressively greater diameter. Disposed within the cylinder structure 18 is a piston member 23, which includes piston portions 24, 25, 26 and 27, which fit within the cylindrical walls 19 to 70 22, respectively.

The piston member 23 is connected to the valve 13 by means of a rod 28, by means of which it controls the valve. The piston member is biased upwardly by a compression 75 spring 29, the upper end of which abuts the piston member and the lower end of which abuts a spring-holding member 30. Suitable means are provided for moving the spring-holding member 30 vertically to vary the 80 spring setting. In the present embodiment, this means includes a tubular member 31, which is screw-threaded within the spring-holding member 30 and which carries a bevel gear 32, and a stub shaft 33 carrying a pinion 34 meshing with the bevel gear 32. A hand wheel 35 is secured on the shaft 33 for 85 rotating the same.

As will be noted from the drawing, the cylinder structure 18 is formed with end wall 90 portions for the upper ends of the cylindrical walls 19 to 22, whereby separate chambers 36 to 39 are formed by the cylinder walls 19 to 22 and the piston portions 24 to 27, respectively.

The piston portion 24 is subjected at all 95 times to the fluid pressure developed by the pump 15, which is transmitted to the chamber 36 by the conduit 17. The fluid pressure provided by the pump 15 is also conveyed through a branch of the conduit 17 to a pas- 100

sage 40, and the chambers 37 to 39 communicate with the passage 40 by means of passages 41 to 43, respectively. Valves 44 to 46 are interposed in the passages 41 to 43, respectively, whereby the variable fluid pressure may be admitted to any one of the chambers 37 to 39 or may be shut off therefrom. Each of the valves is provided with a handle 47 for operating the same.

- 10 The valve 44 is shown in elevation in open position, the valve 45 is shown in section in open position, and the valve 46 is shown in section in closed position. Each of these valves is formed with a recess 48 communicating 15 with a drain passage 49 disposed in back of the plane in which the section is taken. When a valve is in closed position as shown by valve 46, fluid in the chamber communicating therewith may be discharged to the drain 20 and atmospheric pressure is maintained in such chamber.

The operation of the above described apparatus is as follows:

To operate the turbine at the highest speed 25 setting provided by variation in piston surface, each of the valves 44 to 46 is moved to closed position. The variable fluid pressure is now effective only on the piston portion 24. In view of the fact that the pressure is effective 30 on only a comparatively small area, the turbine must attain a relatively high speed in order that the variable fluid pressure may oppose the force of the spring 29. The governor operates in the manner of a fluid pressure governor, as is well known, as follows:

Upon increase in speed the increased fluid pressure provides increased compression of the spring 29 and downward movement of the piston member 23 to effect closing movement of the valve 13. Upon decrease in speed, the compression of the spring 29 is decreased and the piston member 23 moves upwardly to move the valve 13 in opening direction.

45 Assuming now that it is desired to operate the turbine at the next highest speed setting provided by the variable piston area construction, the valve 44 is moved to open position, whereupon the variable fluid pressure is admitted to the chamber 37 and is effective 50 on the upwardly facing surface of the piston portion 25. The area or surface of the piston member 23 on which the variable fluid pressure is effective to bias the piston member 55 downwardly, is now increased. The downward force of the fluid pressure on the piston member is now considerably greater and moves the admission valve in closing direction. The speed of the turbine now decreases, with consequent decrease in fluid pressure, until the force exerted by the variable fluid pressure is approximately equal to the force which was previously exerted by the variable fluid pressure on the piston portion 60 65 24 alone. The governor now governs the

turbine in the same manner but at the lower speed.

To govern at the next higher speed setting, the valve 45 is moved to open position and the variable fluid pressure admitted to the 70 chamber 38 to bias the piston portion 26 also. The governor again operates in the same manner but at a still lower speed setting.

To obtain the lowest speed setting, the valve 46 is opened in addition to the valves 75 44 and 45. The variable fluid pressure is now effective on all of the piston portions and a still lower fluid pressure on the maximum piston area provides the necessary governing 80 force on the piston member.

By making the piston portions 25 to 27 of different areas, and using different combinations of the valves 44 to 46, an increased number of speed settings may be provided.

It is apparent that the same variation in 85 total governing force is required to move the piston member through its travel at all of the various speed settings, inasmuch as the position of the piston member 23 is determined by the deflection of the spring 29. As the variable 90 fluid pressure is proportional to the total governing force, at any one speed setting, the percentage of variation in speed is substantially the same for all speed settings.

It will be apparent that variation in effective 95 piston area permits of variation in speed setting only in steps. In order to vary the speed setting between the steps provided by the variable piston area construction, the setting of the spring 29 may be varied. To do 100 this, the hand wheel 35 is rotated, which rotates the sleeve 31 to raise or lower the spring-holding member 30. This form of adjustment is well known in the art and is suitable for providing gradual change of speed 105 setting within comparatively narrow limits. It may be used to provide change in speed setting from one to the next of the steps provided by the variable piston area arrangement. While a change in the spring setting 110 changes the percentage of regulation somewhat, this is not objectionable as the extent of variation in speed setting by this means is limited. The wide changes in speed setting, for which the spring setting adjustment 115 would interpose objectionable changes in governing characteristics, are provided by the variable piston area which does not effect any change in governing characteristic.

It is apparent that numerous refinements 120 in the details of construction may be embodied in the governor, these being omitted from the drawing for the sake of simplicity.

From the above description, it will be seen that I have provided a simple arrangement 125 for providing substantially the same governing action at speeds which may widely vary.

While I have shown my invention in but one form, it will be obvious to those skilled in the art that it is not so limited, but is 130

susceptible of various changes and modifications without departing from the spirit thereof, and I desire, therefore, that only such limitations shall be placed thereupon as are imposed by the prior art or as are specifically set forth in the appended claims.

What I claim is:

1. In a fluid pressure speed-responsive governing mechanism for governing the speed of a prime mover within the same percentage of speed variation at a plurality of speed settings, the combination of means providing a fluid pressure varying as a function of the speed of the prime mover, pressure-responsive means subjected to said variable fluid pressure and controlling the admission of motive fluid to the prime mover, a spring acting on the pressure-responsive means in opposition to the fluid pressure, and means for varying the area of the surface of the pressure-responsive means subjected to said variable fluid pressure.
2. The combination with a prime mover, of a fluid pressure speed governing mechanism for governing the speed of the prime mover within the same percentage of speed variation at a plurality of speed settings comprising means providing a fluid pressure varying as the square of the speed of the prime mover, means including and controlled by a pressure-responsive element subjected to such variable fluid pressure for controlling the admission of motive fluid to the prime mover, a spring biasing the pressure-responsive element in opposition to said fluid pressure, and means for varying the area of surface of the pressure-responsive element on which the fluid pressure is effective to bias said element.
3. The combination with a prime mover, of fluid pressure speed governing mechanism therefor comprising a cylinder structure having interior cylinder walls of different diameters, a piston member having piston portions fitting said cylinder wall and forming separate chambers therewith, means providing a fluid pressure varying as the square of the speed of the prime mover, means for admitting said variable fluid pressure to said chambers to bias said piston portions, valve means for admitting or shutting off said pressure to one of said chambers, a spring biasing the piston member in opposition to the fluid pressure, and means controlled by said piston member for regulating the admission of motive fluid to the prime mover.

In testimony whereof, I have hereunto subscribed my name this 18th day of October, 1929.

WALTER SCHMID.
